UNITED STATES PATENT OFFICE.

JAMES PHILLIPS, JR., OF FITCHBURG, MASSACHUSETTS.

DESIGN FOR WOVEN FABRIC.

SPECIFICATION forming part of Design No. 24,748, dated October 8, 1895.

Application filed August 14, 1895. Serial No. 559,289. Term of patent 3½ years.

To all whom it may concern:

Be it known that I, JAMES PHILLIPS, Jr., of Fitchburg, in the county of Worcester and State of Massachusetts, have invented and produced a new and original Design for Woven Fabrics, of which the following is a description.

Reference is to be had to the accompanying drawing, which shows a plan view of a woven

o fabric embodying my design.

The leading feature of my design consists in a number of elongated tuft-like figures raised from the body of the fabric and arranged diagonally thereon in lines, the tuft-like figures of alternate lines being inclined

5 in reverse order.

Referring to the drawing, A designates the body of the fabric, and A' A² show the alternating lines of independent elongated tuft-like figures a. The tuft-like figures of each line are substantially parallel one with another, and the said figures of the lines extend diagonally, the trend of the figures in one line being the reverse of the trend of the figures in the adjacent line. 25

I claim—

The design for a fabric substantially as herein shown and described.

JAMES PHILLIPS, JR.
